UNITED STATES PATENT OFFICE

GEORGE A. TUCK, OF SAN FRANCISCO, CALIFORNIA

GAS FURNACE

Application filed May 6, 1930. Serial No. 450,218.

My invention relates to improvements in furnace construction wherein a combustion chamber is provided with a laterally extending expansion chamber and tortuous expansion passage to obtain a large volume for expansion and arranged to set up internal stresses and counter currents within the combustion gases to retard the flow of gas with a minimum restriction of the area of outlet.

10 The primary object of my invention is to provide an improved gas furnace construction.

Another object is to provide an improved furnace construction wherein the normal upward movement of gases of combustion from a gas burner is translated to a lateral movement at substantially right angles to said normal upward movement to retard the flow of expanding gases.

20 A further object is to provide an improved furnace construction wherein a combustion chamber is provided with a laterally extending expansion chamber communicating with the combustion chamber and forming an extension thereof to obtain increased volume for expansion and arranged to direct the flow of gases in a manner to retard the rate of flow with a minimum restriction of the area of outlet.

30 Another object is to provide an improved device of the character described to obtain increased efficiency of combustion and increased heating efficiency.

35 A further object is to provide an improved furnace structure of simple, compact, and efficient construction.

40 A still further object is to provide an improved furnace which may be rapidly heated to full operative efficiency and which effectually prevents condensation within the furnace.

45 I accomplish these and other objects by means of the improved device disclosed in the drawings forming a part of the present application wherein like characters of reference are used to designate similar parts throughout the specification and drawings and in which—

50 Fig. 1 is a transverse sectional view taken

upon the line 1—1 of Fig. 2 in the direction indicated; and

Fig. 2 is a vertical section taken upon the line 2—2 of Fig. 1 in the direction indicated.

Referring to the drawings, the numeral 1 is used to designate in general a combustion chamber provided with a suitable gas burner 2 mounted within the bottom portion thereof. The burner 2 may be of any desired form and size and may be controlled in any desired manner. An air connection 3 is mounted to open into the bottom portion of the combustion chamber 1 to admit air to support combustion of fuel issuing from the burner, said fuel being supplied through a suitable supply pipe 4. The combustion chamber 1 is preferably formed from sheet metal shaped to substantially rectangular cross section, and with its vertical dimension substantially greater than the horizontal dimensions.

55 An expansion chamber 6 is mounted upon one side of the combustion chamber 1. The chamber 6 is preferably formed from sheet metal and arranged to extend laterally from the combustion chamber, said expansion chamber 6 communicating with the combustion chamber 1 through a slot-like opening 7 vertically disposed within the wall of the chamber 1. The bottom of the expansion chamber 6 is arranged slightly above the level of the burner 2, and the chamber 6 preferably extends upwardly to the top of the combustion chamber so that the top of the expansion chamber forms a continuation of the top of the combustion chamber. The 60 opening 7 in the wall of the combustion chamber extends substantially the full height of the expansion chamber and is made relatively narrow with respect to its vertical height.

65 One side wall of the expansion chamber 6 is preferably arranged at right angles to the plane of the adjacent wall of the combustion chamber, and is arranged to match with the adjacent edge of the opening 7. The opposite wall is preferably formed from two wall portions 6' and 6'' converging toward a line of intersection within the chamber 6 to form a restriction within the expansion chamber, at a point spaced from the opening 7. The wall portion 6' inclines inwardly from the adja- 70 75 80 85 90 95 100

cent edge of the opening 7 and the wall portion 6" inclines in the opposite direction to the end of the chamber 6. An outlet opening 8 is formed in the chamber 6, preferably in the wall portion 6" immediately beyond the restriction formed by the wall portion 6'. The opening 8 preferably extends vertically the full height of the expansion chamber and is made relatively narrow so as to provide a vertically disposed slot-like outlet.

10 A tortuous gas expansion passage 9 formed between spaced parallel wall portions is mounted with one end communicating with the outlet opening 8, the vertical walls of said passage 9 being spaced substantially the same as the width of the opening 8, and extending the full height of the expansion chamber. The passage 9 is extended beyond the outer end of the expansion chamber and is shaped to curve or extend around the end of the expansion in spaced relation to the walls thereof to form a relatively restricted air passage 11 between the adjacent walls of the passage and expansion chamber.

25 A tortuous flue passage, preferably consisting of a pair of vertically disposed parallel flue chambers 12 and 13, is mounted with the lower end of the chamber 12 connected to communicate with the lower portion of the tortuous expansion passage 9 through a suitable connection 14 connected into said passage at the end remote from the opening 8 of the expansion chamber. The chambers 12 and 13 are connected at the top by a suitable connecting passage 16. A stack connection 17 is connected into the bottom of the chamber 13, said connection 17 being extended to any suitable stack. The chambers 12 and 13 are preferably of substantially the same height as the expansion chamber 6 and passage 9, and are spaced from each other and from the adjacent portion of the passage 9 to provide air passages through which air may circulate upwardly past the heated walls of the chambers.

40 The combustion chamber 1 and expansion chamber 6, together with the tortuous passage 9 and flue chambers 12 and 13, are encased together in an outer casing 19 preferably of double walled sheet metal structure consisting of outer and inner walls 18 and 18' spaced to provide an air space 18" to insulate the casing.

45 Air to be heated is admitted into the case-
ment 18 through suitable air inlet connections 19 mounted within the lower portion of the casing, preferably at the back thereof. The air entering the casing circulates upwardly around the several chambers and passages and is heated by contact with the surfaces thereof, the heated air rising upwardly through the casing and passing outwardly through a suitable outlet 21 mounted within the top of the casing.

50 In operation, fuel issuing from the burner

2 is ignited and burns in the ordinary manner, air being admitted through the connection 3 to obtain a complete combustion of the fuel. The heated products of combustion rise vertically from the burner 2 toward the top of the combustion chamber 1 at the same time expanding within the chamber 1. The normal trend of movement may be likened to a sheet of gaseous products spread in a horizontal plane across the combustion chamber 75 and rising vertically toward the top of the chamber. As the rising products move past the slot-like opening 8 in the wall of the chamber, the gases expand and are moved laterally through said opening into the expansion chamber. This expansion and flow through the opening 8 occurs along the full height of the opening 8 and expansion chamber 6, and the movement of the gases into the expansion chamber may be likened to a sheet of gaseous material disposed in a vertical plane and moving horizontally into the expansion chamber. Thus the movement of gases is translated from a normal upward 90 trend to a lateral movement in a horizontal direction along a vertical plane at substantially right angles to the normal upward movement. The resistance of the upwardly rising gases to lateral displacement, together with eddy currents and internal resistance to this translation of movement retards the flow of gases from the combustion chamber sufficiently to insure a complete and efficient combustion of fuel within the combustion chamber. At the same time, the relatively large area of the vertical slot 8 permits the gas to expand into the expansion chamber 6 without creating sufficient back pressure within the combustion chamber to cause hovering flame and inefficient combustion, the effect being to provide an increased volume for expansion of the gases while still operating to retard the flow sufficiently to insure efficient combustion without causing back pressure such as occurs in the case of an outlet of relatively small and restricted area.

95 The gases flowing into the expansion chamber 6 expand within the chamber and into the tortuous expansion passage 9 through the outlet 8. Gases expanding within the end of the chamber 6 remote from the opening 8 must expand against the pressure of incoming gases in order to reach the outlet opening 8. The result is that the incoming gases are crowded toward the side of the chamber opposite the outlet opening 8, and the flow of incoming gases is retarded by the expansion of gases within the expansion chamber and at the same time, said inflowing gases retard the expansion of the gases within the chamber and retard the flow of said gases to the outlet. This action is increased by the structure and arrangement of the wall portions 6' and 6" as above described. The inclined wall portion 6' de- 100

130

fects the incoming gas toward the side of the chamber 6 opposite the outlet opening 8, and at the same time causes a slight restriction operating to impart an increased velocity to the incoming gases passing the outlet 8. The opening 8 is formed in the wall 6" immediately beyond the edge of the wall 6' so that said wall overhangs the adjacent edge of the wall portion 6" whereby the incoming gas is deflected past the stream of outflowing gases and insuring an efficient circulation of gas through the enlarged portion of the chamber 6 beyond the outlet 8.

The gases entering the expansion passage 9 continue to move through said passage as a vertically disposed sheet moving horizontally along the passage, the direction of movement being shifted first at right angles as the gases pass from the expansion chamber into the passage, and then being directed along the tortuous course of the passage, as illustrated in preferred form in the drawings. The opening 8 and passage 9 are of substantially the same height as the chamber 6, said passage forming a continuation of the expansion chamber, and thereby affording still greater volume for expansion in which the flow of gases is retarded by internal stresses set up within the gases rather than by a positive restriction of the area of outlet. This structure and arrangement permits the expansion chamber and expansion passage 9 to be heated very rapidly, thereby preventing condensation of moisture from the gases when the furnace is started from a cold condition.

The tortuous flue passage chambers 12 and 13, with their connecting passages 14 and 16, receive the gases after they have been partially cooled during their movement through the expansion chamber and expansion passage. The movement of the gases is translated from the horizontal movement within the expansion chamber to an upward vertical movement within the chamber 12 and a downward vertical movement in the chamber 13. The connecting passages 14 and 16 are made of relatively large area, as compared to the size of similar passages in furnace structures heretofore embodying a tortuous flue, in order to impose as little positive restriction as possible to flow of gases through the furnace. The restriction of the outlet area through the connections 14 and 16 occurs after the gases have been afforded time to fully expand and to give up the greater portion of their heat to the walls of the combustion and expansion chambers and their tortuous passage 9.

For heating purposes, air is admitted into the casing 18 through the air inlets 19. This air circulates upwardly through the casing 18 around the several chambers and passages and through the air circulating spaces between the chambers 12 and 13, and through the air 11 between the walls of the

chamber 6 and passage 9. The air is thus exposed to contact with a wide area of heated surface, thereby causing the air to be rapidly and efficiently heated. The heated air passes outwardly through the outlet 21 for delivery to rooms to be heated in any convenient manner.

While I have illustrated and described what I now regard as the preferred embodiment of my invention, the device is of course subject to modification in numerous ways without departing from the spirit of my invention. I therefore do not wish to restrict myself to the specific details of construction and arrangement disclosed, but desire to avail myself of all modifications which may fall within the scope of the appended claims.

Having thus described my invention, what I claim as new and desire to secure by Letters Patent is:

1. A gas furnace comprising a combustion chamber provided with a burner mounted within the bottom thereof; an expansion chamber extending laterally from the combustion chamber and communicating with said combustion chamber through an opening having the greatest dimension vertically disposed in the side of the combustion chamber to translate a normal upward movement of gases of combustion within the combustion chamber to a lateral movement in a plane substantially at right angles to said normal upward movement; and a tortuous passage connected into the expansion chamber to conduct the gases to a stack.

2. A gas furnace comprising a combustion chamber provided with a burner mounted within the bottom thereof; an expansion chamber extending laterally from the combustion chamber and communicating with said combustion chamber through an opening having its greatest dimension vertically disposed in the side of the combustion chamber, to translate a normal upward movement of gases of combustion, within the combustion chamber, to a lateral movement in a plane substantially at right angles to said normal upward movement; and a tortuous passage connected into the expansion chamber at a point intermediate to the ends of the expansion chamber to permit expansion therefrom along a vertical plane.

3. A gas furnace comprising a combustion chamber provided with a burner mounted within the bottom thereof; an expansion chamber extending laterally from the combustion chamber and communicating with the combustion chamber through an opening having its greatest dimension vertically disposed in the side of the combustion chamber to translate a normal upward movement of gases of combustion, within the combustion chamber, to a lateral movement in a plane substantially at right angles to said normal upward movement, said expansion chamber

being provided with a restricted portion between the combustion chamber and the outer end of the expansion chamber; and a tortuous passage connected into the expansion chamber at a point intermediate the ends of the expansion chamber to permit expansion therefrom along a vertical plane.

4. A gas furnace comprising a combustion chamber provided with a burner mounted within the bottom thereof; an expansion chamber extending laterally from the combustion chamber and communicating with the combustion chamber through an opening having its greatest dimension vertically disposed in the side of the combustion chamber to translate a normal upward movement of gases of combustion, within the combustion chamber, to a lateral movement in a plane substantially at right angles to said normal upward movement, said expansion chamber being provided with a restricted portion between the combustion chamber and the outer end of the expansion chamber; and a tortuous passage connected into the expansion chamber at a point immediately outwardly from the restricted portion of the expansion chamber.

5. A gas furnace comprising a combustion chamber provided with a burner mounted within the bottom thereof; an expansion chamber extending laterally from the combustion chamber and communicating with the combustion chamber through a vertically disposed slot in the side of the combustion chamber to translate a normal upward movement of gases of combustion within the combustion chamber to a lateral movement in a plane substantially at right angles to said normal upward movement, said expansion chamber being provided with a restricted portion spaced from the combustion chamber; a tortuous expansion passage connected into the expansion chamber through a vertically disposed slot within the restricted portion of the expansion chamber, said slot extending substantially the full height of the expansion chamber to permit lateral expansion and movement of the gases from the expansion chamber along a vertical plane.

6. A gas furnace comprising a combustion chamber provided with a burner mounted within the bottom thereof; an expansion chamber extending laterally from the combustion chamber and communicating with the combustion chamber through a vertically disposed slot in the side of the combustion chamber to translate a normal upward movement of gases of combustion within the combustion chamber to a lateral movement in a plane substantially at right angles to said normal upward movement, said expansion chamber being provided with a restricted portion spaced from the combustion chamber; a tortuous expansion passage connected into the expansion chamber through a verti-

cally disposed slot within the restricted portion of the expansion chamber, said slot extending substantially the full height of the expansion chamber to permit lateral expansion and movement of the gases from the expansion chamber along a vertical plane; and a tortuous flue passage connected to the tortuous expansion passage to translate the lateral movement of gases to a vertical movement.

7. A gas furnace comprising a combustion chamber provided with a burner mounted within the bottom thereof; an expansion chamber extending laterally from the combustion chamber and communicating with the combustion chamber through a vertically disposed slot in the side of the combustion chamber to translate a normal upward movement of gases of combustion within the combustion chamber to a lateral movement in a plane substantially at right angles to said normal upward movement, said expansion chamber being provided with a restricted portion spaced from the combustion chamber; a tortuous expansion passage connected into the expansion chamber through a vertically disposed slot within the restricted portion of the expansion chamber, said slot extending substantially the full height of the expansion chamber to permit lateral expansion and movement of the gases from the expansion chamber along a vertical plane; a tortuous flue passage connected to the tortuous expansion passage, said flue passage comprising a vertically disposed passage provided with a connection, adjacent to the bottom thereof, opening into the bottom of the expansion passage, and a second vertical flue passage spaced from the first flue passage and provided with a connection at the top to communicate with the top of said first flue passage, and a stack outlet formed at the bottom of the second flue passage, said flue passages operating to translate the lateral movement of gases in the expansion passage to vertical movement in said flue passages.

8. A gas furnace comprising a combustion chamber provided with a burner mounted within the bottom thereof; an expansion chamber extending laterally from one side of the combustion chamber; a gas outlet formed in the side of the combustion chamber and communicating with the expansion chamber, said outlet comprising a vertically disposed slot-like opening in the side of the combustion chamber and extending substantially the full height of the expansion chamber to translate a normal upward movement of gases of combustion within the combustion chamber to a lateral movement in a plane substantially at right angles to said normal upward movement; angularly disposed wall portions forming one side of the expansion chamber and converging toward a

line of intersection within the expansion chamber and having a vertically disposed outlet opening formed in one of said inclined wall portions adjacent the line of intersection; and a tortuous expansion passage communicating with the expansion chamber through said vertical slot.

9. A gas furnace comprising a combustion chamber provided with a burner mounted 10 within the bottom thereof; an expansion chamber extending laterally from one side of the combustion chamber; a gas outlet formed in the side of the combustion chamber and communicating with the expansion 15 chamber; said outlet comprising a vertically disposed slot-like opening in the side of the combustion chamber and extending substantially the full height of the expansion chamber to translate a normal upward movement 20 of gases of combustion within the combustion chamber to a lateral movement in a plane substantially at right angles to said normal upward movement; angularly disposed wall portions forming one side of the 25 expansion chamber and converging toward a line of intersection within the expansion chamber and having a vertically disposed outlet opening formed in one of said inclined wall portions adjacent the line of intersection; a tortuous expansion passage communicating 30 with the expansion chamber through said vertical slot, said passage being of substantially the same height as the expansion chamber and being shaped to extend around 35 the outer end of said expansion chamber to conduct gases laterally along a vertical plane and to provide a restricted air circulating space between the walls of said expansion chamber and passage.
- 40 10. A gas furnace comprising a combustion chamber provided with a burner mounted within the bottom thereof; an expansion chamber extending laterally from one side of the combustion chamber; a gas outlet formed in the side of the combustion chamber and communicating with the expansion chamber, said outlet comprising a vertically disposed slot-like opening in the side of the combustion chamber and extending substantially the full height of the expansion chamber to translate a normal upward movement of gases of combustion within the combustion chamber to a lateral movement in a plane substantially at right angles to said normal upward movement; angularly disposed wall portions forming one side of the expansion chamber and converging toward a line of intersection within the expansion chamber and having a vertically disposed outlet opening 45 formed in one of said inclined wall portions adjacent the line of intersection; a tortuous expansion passage communicating with the expansion chamber through said vertical slot, said passage being of substantially the same height as the expansion chamber and being

shaped to extend around the outer end of said expansion chamber to conduct gases laterally along a vertical plane and to provide a restricted air circulating space between the walls of said expansion chamber and passage; and a tortuous flue passage mounted adjacent the expansion passage and provided with a connection communicating with said expansion passage.

11. A gas furnace comprising a combustion chamber provided with a burner mounted within the bottom thereof; an expansion chamber extending laterally from one side of the combustion chamber; an outlet formed in the side of said combustion chamber and opening into the expansion chamber, said outlet comprising a vertically disposed slot in the side of the combustion chamber and extending substantially the full height of the expansion chamber to translate a normal upward movement of gases of combustion within the combustion chamber to a lateral movement within the expansion chamber in a plane substantially at right angles to said normal upward movement, said expansion 85 chamber being provided with one side wall at right angles to the side of the combustion chamber and the opposite wall being formed in angularly disposed wall portions converging toward a line of intersection with the 90 chamber to form a restriction intermediate the ends of the chamber; and a tortuous passage connected into the expansion chamber through a vertically disposed slot formed in the inclined wall portion remote from the 95 combustion chamber.

12. A gas furnace comprising a combustion chamber provided with a burner mounted within the bottom thereof; an expansion chamber extending laterally from one side of the combustion chamber; an outlet formed in the side of said combustion chamber and opening into the expansion chamber, said outlet comprising a vertically disposed slot in the side of the combustion chamber and extending substantially the full height of the expansion chamber to translate a normal upward movement of gases of combustion within the combustion chamber to a lateral movement within the expansion chamber in a plane substantially at right angles to said normal upward movement, said expansion chamber being provided with one side wall at right angles to the side of the combustion chamber and the opposite wall being formed in angularly disposed wall portions converging toward a line of intersection within the chamber to form a restriction intermediate the ends of the chamber; a tortuous passage connected into the expansion chamber through a vertically disposed slot formed in the inclined wall portion remote from the combustion chamber, the adjacent end of the other inclined wall portion being extended to inwardly offset relation to the edge of the outer in- 130

clined wall portion to deflect the gases entering the expansion chamber past the opening into the tortuous passage.

13. In a gas furnace, the combination with 5 a combustion chamber having a burner mounted within the bottom portion thereof, of an expansion chamber formed upon one side of the combustion chamber and communicating with said chamber through slot-like opening in the side of said combustion chamber, said opening having its vertical dimension relatively great with respect to its horizontal dimension to translate a normal upward movement of gases of combustion 15 within the combustion chamber to a lateral movement in a vertical plane substantially at right angles to said upward movement during the course of said upward movement.

14. In a gas furnace, the combination with 20 a combustion chamber having a burner mounted within the bottom portion thereof, of an expansion chamber formed upon one side of the combustion chamber and communicating with said chamber through a vertically disposed slot-like opening in the side of said combustion chamber to translate a normal upward movement of gases of combustion within the combustion chamber to a lateral movement in a plane substantially 25 at right angles to said upward movement; and a tortuous expansion passage connected into one side of the expansion chamber through a vertically disposed slot-like opening formed therein, the openings and the tortuous passage being of substantially the same 30 height as the expansion chamber.

15. In a gas furnace, the combination with a combustion chamber having a burner mounted within the bottom portion thereof, 40 of an expansion chamber formed upon one side of the combustion chamber and communicating with said chamber through a vertically disposed slot-like opening in the side of said combustion chamber to translate a normal upward movement of gases of combustion within the combustion chamber to a lateral movement in a plane substantially 45 at right angles to said upward movement; a tortuous expansion passage connected into 50 one side of the expansion chamber through a vertically disposed slot-like opening formed therein, the openings and the tortuous passage being of substantially the same 55 height as the expansion chamber; and deflecting means for deflecting gases entering the expansion chamber from the combustion chamber, and to form a restricted passage within said expansion chamber, to obtain 60 an increased velocity of gases entering the expansion chamber past the opening from said expansion chamber into the expansion passage and to set up internal stresses within the gases, and thereby retard the flow of 65 gas moving outwardly from the expansion

chamber into said tortuous expansion passage.

16. In a gas furnace, the combination with a combustion chamber provided with a burner mounted within the bottom thereof, of 70 an expansion chamber mounted upon one side of the combustion chamber and communicating with said combustion chamber through a slot-like opening having a vertical dimension great with respect to its horizontal dimension; and a tortuous passage connected into one side of the expansion chamber and communicating with said expansion chamber through a slot-like opening substantially the same height as the expansion chamber and 75 of relatively narrow width.

17. In a gas furnace, the combination with a combustion chamber provided with a burner mounted within the bottom thereof, of an expansion chamber mounted upon one side of the combustion chamber and communicating with said combustion chamber through a slot-like opening having a vertical dimension great with respect to its horizontal dimension; a tortuous passage connected 80 into one side of the expansion chamber and communicating with said expansion chamber through a slot-like opening of substantially the same height as the expansion chamber and of relatively narrow width; said tortuous passage being of substantially the same height as the expansion chamber and being shaped to extend around the outer end of the expansion passage with the adjacent walls of the passage and expansion chamber in spaced relation to provide an air circulating passage therebetween.

18. In a gas furnace, the combination with a combustion chamber provided with a burner mounted within the bottom thereof, of an 105 expansion chamber mounted upon one side of the combustion chamber and communicating with said combustion chamber through a slot-like opening having a vertical dimension great with respect to its horizontal dimension; a tortuous passage connected into one side of the expansion chamber and communicating with said expansion chamber through a slot-like opening of substantially 110 the same height as the expansion chamber and of relatively narrow width, said tortuous passage being of substantially the same height as the expansion chamber and being shaped to extend around the outer end of the expansion passage with the adjacent walls 115 of the passage and expansion chamber in spaced relation to provide an air circulating passage therebetween; and a tortuous flue passage connected into the lower portion of the tortuous passage at the end remote from 120 the expansion chamber.

In witness whereof, I hereunto set my signature.

GEORGE A. TUCK.
